UNITED STATES PATENT OFFICE

2,664,574

SOFA BED WITH FORWARD TURNING BACK

John Teasdale Newborn, London, England, assignor to Vi-Spring Products Limited, London, England

Application September 11, 1950, Serial No. 184,219

Claims priority, application Great Britain
September 14, 1949

1 Claim. (Cl. 5—43)

1

The invention relates to seats, settees and the like, of the kind comprising a seat portion and a back portion upstanding therefrom in which the back portion is arranged to move relative to the seat portion to a generally horizontal position in which it provides a support for a mattress or the like to constitute a bed or bunk.

It is an object of the invention to provide an improved seat of the kind described which is particularly suitable for use where space is restricted, e. g. in ships, trains, motor coaches and other vehicles.

The invention provides in one aspect a seat, settee or the like, of the kind described, in which the back portion is supported for pivotal movement about a substantially horizontal axis above the level of the seat portion, so that it may be rotated from its upstanding position to a substantially horizontal position in which it lies partly above the seat portion with its rear face directed upwardly, and in which means are provided for moving the back portion and its pivotal axis over the seat portion during the aforesaid rotational movement.

This arrangement has, among others, the advantage that the back portion, when in the upright position, may extend downwardly behind the rear of the seat portion, and that during the movement of the back portion to the horizontal or bed position, the lower edge of the back portion may be constrained to follow a substantially vertical path, or preferably, an upward path with a rearwards component so that when in the bed position the edge is located within a recess provided behind the back portion, which recess is for the purpose of accommodating the thickness of the back portion, or a mattress thereon, when in the upright position.

The aforesaid pivotal axis is preferably itself movable by a swinging movement about a parallel axis above it.

In the preferred form of the invention, the back portion is suspended from a support by links movable in substantially vertical planes and pivoted at their upper ends to the support near the top of the back portion and pivoted at their lower ends to the back portion at a position intermediate in the height of the back portion between the upper pivots and the top of the seat portion, the upper and lower pivotal axes extending horizontally and lengthwise of the back portion and the lower edge of the back portion has means co-operating with a cam surface provided on the support to move the back portion forward over the seat portion with corresponding swinging move-

2

ment of the links, as the back portion is rotated about the lower ends of the links.

A specific construction of a seat convertible into a bed and embodying the invention will now be described by way of example and with reference to the accompanying drawings, in which:

Figure 1 is a plan view, partly broken away, showing one end of the settee when converted into a bed;

Figure 2 is a view in the direction II—II in Figure 1, and

Figure 3 is a view in the direction III—III in Figure 1 but showing the parts, some in broken lines, moved to provide the settee.

In this example, the seat comprises a seat portion 1 and a back portion 2. The seat portion 1 is supported on horizontal bearers 3 and comprises a sprung upholstered unit having a seat base 4 of spring units, an intermediate layer 5 comprising a large number of small helical springs each contained in a separate fabric or other flexible pocket, and an upper layer 6 of upholstery comprising, for example, felt, or 25 curled hair.

The back portion 2 comprises a frame 7 supporting a spring unit 8 having on one side thereof a spring upholstered back rest unit comprising spring units 9. On the other side (i. e. the rear face) of the spring unit 8 the back portion 2 comprises a pocketed spring mattress 11. The spring unit 8 serves as a resilient support for the mattress and also for the back rest unit. The mattress 11 is located in position on the back portion by channel members 12 and facing boards 13 and 14, and is held, with the bed-clothes, by two straps 19 when the back portion is in the upright position.

The back portion 2 is suspended from a vertical support 15 by links 16 at each end of the back pivoted at their lower ends to the back portion at 17 and pivoted at their upper ends to the support 15 at 18. The back portion 2 carries at each end a rotatable roller 21 which runs along cam surfaces 22 as the back portion 2 is rotated about the pivots 17. The surface 19 of the back portion is convexly arcuate about the axis of the pivots 17.

When the back portion is rotated about the pivots 17 from its upstanding position (Figure 3), the rollers 21 run up the cam faces 22 and move the back portion 2 forward over the seat portion 1, the links 16 simultaneously rotating about the pivots 18 to permit the forward movement of 55 the back portion. When the back portion has

reached its horizontal position (as shown in Figure 2) the rollers 21 are received within channels or notches 23 by a slight backward movement of the back portion, thereby retaining the back portion in the horizontal position so that a person may recline on the mattress 11. When in this position the surface of the back rest unit contacts the seat portion.

When the back portion 2 is in the "settee" position shown in Figure 3 a spring ball detent 25 engages in a recess on the pivot pin 18 to retain the portion in position.

The invention is not restricted to the details of the foregoing example. For instance, another unit, similar to the back portion 2 but without the seat may be provided vertically above the back portion 2 so that a two-tier bunk is thereby provided.

I claim:

A bed convertible to a seat and comprising a support frame, an elongated seat portion supported in fixed relation by the frame, a horizontal bed portion overlying the seat portion, substantially in contact with the upper surface thereof and extending to the rear thereof, the 25 length of the bed extending lengthwise of the seat portion, links movable in a vertical plane supporting the bed portion in hanging relation from the frame and pivoted at their upper ends to the frame at a position above the bed portion and pivoted at their lower ends to the bed portion at a position which overlies the seat portion, is spaced from the upper surface thereof and is further from the rear edge of the bed portion than it is from the surface of the seat por- 35

tion, the under surface of the bed portion towards the rear edge from the pivot axis being convexly arcuate about the pivot axis, a cam surface secured to the frame and extending downwardly from a position adjacent the rear edge of the bed portion and forwardly near its lower end, the cam surface having a rearwardly extending notch at its upper end, and a cam follower on the rear edge of the bed portion engaged within the notch, the bed portion being movable from the horizontal position aforesaid by disengagement of the follower from the notch and by pivotal movement about the attachment to the lower ends of the links with rolling movement of the aforesaid arcuate surface over the seat and by co-operation of the follower with the cam surface accompanied by swinging movement of the links, into a position in which the bed portion has its width extending upwardly and constitutes a back for the seat, the lower edge of the bed portion extending below and behind the seat portion.

JOHN TEASDALE NEWBORN.
